UNITED STATES PATENT OFFICE.

EMMET NICHOLS, OF PARIS, ILLINOIS.

HEATER FOR STOCK-WATERING TANKS.

Application filed November 26, 1921. Serial No. 517,845.

To all whom it may concern:

Be it known that I, EMMET NICHOLS, a citizen of the United States, residing at Paris, in the county of Edgar and State of Illinois, have invented certain new and useful Improvements in Heaters for Stock-Watering Tanks; and I do hereby declare the following to be a full, clear, and exact description of the invention, such as will enable others skilled in the art to which it appertains to make and use the same.

My invention relates to certain new and useful improvements in heaters, and more particularly stated contemplates the production of a portable heater arranged and adapted to effect the circulation of water, such for example, as that used in stock watering tanks.

An object of the present invention is to provide a compact and readily handled heating device which can be positioned in an animal watering tank to prevent freezing of the water in winter weather.

Another object of my invention is the production of a self-contained heating unit embodying combustion chamber, grate, ash pan, and associated water circulating passageway through which latter the water is caused to pass as the temperature of the water rises.

A further object of the invention is to produce a comparatively simple and easily cleaned portable heater, which can be inexpensively manufactured.

A still further object of the invention is to design a heater of a shape and size capable of relatively long and effective periods of use in extremely cold weather.

Other objects will in part be obvious from the specification and appended claims, reference also being had to the accompanying drawings, in which—

Figure 1 is a vertical sectional view through my improved heater;

Figure 2 is a top plan view thereof with the lid removed;

Figure 3 is a vertical sectional view of the container or bowl; and

Figure 4 is a top plan view of the ash receiver or pan.

Referring to the drawings in which similar reference characters designate corresponding parts in the several views, the

heating apparatus comprises a container or bowl formed with supporting legs or base 55 2, a compartment 3 for the reception of the ash receiver, and the chamber 4, termed for purposes herein, the combustion chamber.

The container 1 is preferably cylindrical 60 in cross section, being provided with a draft passage 5 at one side thereof, and open at the top as shown for the reception of the lid 6. The chamber 4 is of a size sufficiently large to permit relatively slow but ample 65 combustion.

In the combustion chamber 4 and more particularly at the lower portion thereof, I arrange a coil 7, said coil being adapted to form a water circulating passageway 8. 70 The coil 7 is of standard pipe having at each end elbow fittings connected to the respective inlet and outlet pipes 10 and 11. The inlet and outlet pipes or nipples extend through openings in the walls of the container, and asbestos or other water-tight washers 12 are positioned around said pipes and held in place by nuts 13 to prevent the leakage of any water into the container 1. The inlet pipe 10 is located relatively close 75 to the bottom of the combustion chamber and is designed to be always immersed in the liquid to be heated. The outlet pipe 11 is preferably located upon the opposite side of the container above the inlet openings. 80 I have shown four coils of piping in the present embodiment but it will be understood that various other lengths, sizes and shapes of pipe or other conduits cast or otherwise, may be substituted to provide a 85 suitable water circulating passageway. 90

I prefer to use the coil 7 so as to obtain maximum efficiency from the heat in the combustion chamber, and at the same time afford a simple construction which can be 95 readily inspected and repaired.

The grate 14 is positioned within the coil 7 and is in the form of a circular frusto-conical basket provided with an annular wall having slots 15 and a bottom having slots 100 16. The material to be burned is positioned within the basket and a constant and ample draft is obtained through the aforesaid slotted portions.

The grate is designed to be supported 105 upon the ash receiver 17, and more es-

pecially upon the inwardly projecting fins 18 clearly shown in Figure 4. These fins are designed to support the grate at a height approximating the top of the ash pan (see Figure 1).

The ash receiver or pan 17 is frustoconical and circular, and of a diameter sufficiently large to receive the ashes from the fuel consumed in the grate 14. A handle 19 is provided on the ash pan, and as shown may be cast integral therewith. The compartment 3 which receives the ash pan is formed to readily receive the ash pan and the flaring of the walls of the casing at the top of the said compartment 3 permits of the easy depositing of the ash pan therein.

The lid 6 is formed with a depending flange 20 which fits within and against the inner face of the cylindrical wall of the container. A shoulder 21 is provided centrally of the lid and is adapted to receive a stove pipe with ventilator top and cap (not shown) to keep out rain and snow. Handles 22 are provided on the lid.

Handles 23 are also provided on the container 1 as shown, for facilitating the handling of the heater. The handles are formed of bent rods, the ends of which are threaded and receive nuts upon the inside 30 and outside of the container and lid, as shown.

In assembling the parts of the heater, the ash pan is first lowered into the compartment 3. The grate 14 is then filled with burning coal or other fuel and lowered until it rests upon the fins 18 of the ash pan. The lid 6 is then fitted in place, and the heater is now partially submerged into the watering tank. It will be noted that the extension provided on the lid serves as a damper for the upper end of the draft passage 5. In practice the inlet opening 10 is submerged beneath the level of the water. The outlet opening 11 may or may not be wholly submerged, it being desirable, however, to submerge the outlet in order to obtain a proper circulation of the water. When a sufficient temperature has been reached the water will circulate through the inlet 10 into and through the coil 7 and out the pipe 11. It is this circulation of the water in freezing weather which prevents the freezing of said water, thereby insuring drinking water for the stock. The quantity of fuel may be varied to provide relatively long or short heating periods, the draft 5 and opening at the bottom thereof serving to produce a down draft. The opening 21 forms the outlet passageway for the escape of the smoke or products of combustion.

Changes within the scope of my invention may be made and I do not wish to be understood as limiting myself to the exact construction herein set forth.

I claim:

1. A portable water heater adapted to be placed in a liquid contained in a tank and including an imperforate container having an open upper end, the lower portion of said container being of reduced diameter, an ash receiver arranged in the lower portion of the container and removable through the open upper end of the latter, a receptacle arranged in the container above said ash receiver and forming a grate, a liquid circulating coil arranged in the container and having its ends extending through the wall of the container and open to permit liquid contained in said tank to circulate therethrough, a downdraft flue formed integral with the container and having a portion of its wall formed by the wall of the container, the inner circumference of said coil being of sufficient size to permit the grate and ash receiver to be removed through the upper end of the container, and a cover for said container having an outlet opening and provided with an integral portion functioning as a damper for the upper end of said flue.

2. A portable water heater adapted to be placed in a liquid contained in a tank and including a pot-shaped container having an open upper end, the lower portion of said container being of reduced diameter, an ash receiver arranged in the lower portion of said container and adapted to receive ashes falling from the larger portion of the container, a receptacle arranged in the container, supported by said ash receiver and forming a grate, a liquid circulating coil arranged in the container and having its ends extending through the wall of the container and opened to permit liquid contained in said tank to circulate therethrough, a down-draft flue opening into said container and having one of its walls formed by the wall of the container, the inner circumference of said coil being of sufficient size to permit the grate and ash receiver to be removed through the upper end of the container, and a cover for said container and flue.

3. A portable water heater adapted to be placed in a liquid contained in a tank and including an imperforate container having an open upper end, the lower portion of said container being of reduced diameter and the interior surface of the container gradually flaring from the reduced lower portion to the larger portion of said container, an ash receiver removably arranged in the lower portion of said container, a receptacle arranged in the container above said ash receiver and forming a grate, a liquid circulating coil arranged in the container and having its ends extending through the wall of the container and open to permit liquid contained in said tank to circulate there-

through, a down draft flue formed integral with the container and arranged on the exterior thereof, the inner circumference of said coil being of sufficient size to permit 5 the grate and ash receiver to be removed through the upper end of the container, and a cover for said container having an outlet opening and provided with an integral por-

tion adapted to function as a damper for the upper end of said flue.

In testimony whereof I affix my signature, in presence of two subscribing witnesses.

EMMET NICHOLS.
